UNITED STATES PATENT OFFICE.

FLOYD J. PARKER, OF ROCHESTER, NEW YORK.

HEEL FOR BOOTS OR SHOES.

SPECIFICATION forming part of Letters Patent No. 653,395, dated July 10, 1900.

Application filed January 29, 1900. Serial No. 3,214. (No model.)

To all whom it may concern:

Be it known that I, FLOYD J. PARKER, a citizen of the United States, residing at Rochester, in the county of Monroe and State of New York, have invented new and useful Improvements in Heels for Boots or Shoes, of which the following is a specification.

My invention relates to boots and shoes, and more particularly to the heels thereof.

10 It contemplates the provision of a heel made up of a body permanently connected to a boot or shoe and an outer section which is securely held against casual disconnection from the body and yet is adapted to be readily removed when desired, the said outer or removable section being provided with a tap layer of leather and being designed to be replaced when desired by a similar section having a tap layer of rubber or other material

20 calculated to prevent slipping.

With the foregoing in mind the invention will be fully understood from the following description and claims when taken in conjunction with the annexed drawings, in

25 which—

Figure 1 is a transverse sectional view of my improved heel, taken in the plane indicated by the broken line 1 1 of Fig. 2. Fig. 2 is a section from front to back, taken in the 30 plane indicated by the broken line 2 2 of Fig. 1. Fig. 3 is a perspective view illustrating the body portion of the heel. Fig. 4 is a similar view of the removable section thereof. Fig. 5 is a detail front elevation of the heel. Fig. 6 is a perspective view of the fastener for securing the removable section against 35 casual disconnection. Fig. 7 is a longitudinal section of a heel embodying a modification of my invention.

40 Referring by letter to said drawings, A is a portion of a boot or shoe, and B is the body or permanently-connected section of my improved heel. This body is of the ordinary shape and is made up of an inner layer of 45 leather *a* and an outer metallic frame *b*, the same being connected together and to the bottom *c* of the boot or shoe through the medium of screws *d*, which extend through the shoe bottom and leather layer *a* and take into 50 threaded apertures *e* in the metallic frame, as illustrated. The said metallic frame com-

prises a curved portion *f*, having a groove *g* in its inner side, and a front cross-bar *h*, provided with a vertically-disposed aperture *i* and a recess *p*, in its under side in communication with said aperture for a purpose presently described. It is smaller in size than the leather layer *a* and is surrounded and hidden from view, except at the front of the heel, by a curved strip of leather *k*, arranged below and connected to the leather layer *a*, as shown.

C is the removable section of the heel. This removable section is also of the general shape common to shoe-heels and comprises a tap layer *l* of leather and an inner metallic frame 65 or plate *m*, which are connected together by screws *n*, extending through the leather tap and into threaded apertures in the metallic frame or plate, as shown in Fig. 1. The frame or plate *m* is shaped in conformity to the 70 frame *b* of the body or permanently-connected section B and is provided on its curved edge *p* with an outwardly-extending flange *q*, which is designed to slide into the groove *g* of said frame *b* and hold the removable section to 75 the body or permanently-connected section after the manner shown in Figs. 1 and 2.

Any suitable means, such as one or two screws, may be employed in order to hold the removable section C against sliding with respect to the body or permanently-connected section B, and thereby prevent casual disconnection of the removable section from the body. I prefer, however, to employ for this purpose the fastener D. (Best shown in Fig. 85 6.) The said fastener comprises a cylindrical body *r*, which is designed to normally rest in the aperture *i* of the frame *b* and an aperture *s* in frame or plate *m*, and a lateral finger-piece *t*, which is designed to normally rest in the 90 recess *j* of said frame *b*. When the fastener-body *r* rests in the apertures *i* of the frames *b* and *m* and the finger-piece *t* occupies the recess *j* in frame *b*, as shown in Fig. 5, the fastener is held against vertical movement 95 and is enabled to effectually prevent the section C from sliding with respect to the body or permanently-connected section B. When, however, the fastener is turned through the medium of its lateral projection *t* until said 100 projection is in line with a notch *v* in frame *b*, the fastener may be moved up and out of

the seat *s* in frame *m*, after which the section *C* of the heel may be readily slid out of engagement with the body or permanently-connected section *B*.

5 The section *C* of my improved heel is made removable in order that when desired it may be readily removed and replaced by a similar section, which I have not deemed it necessary to illustrate, having a tap layer of rubber instead of one of leather.

By virtue of the construction described it will be seen that when the wearer of shoes equipped with my improvements desires to safely walk upon ice or a slippery pavement 15 he has but to remove the heel-sections *C*, having leather tap layers, and replace the same with similar sections having tap layers of rubber or other material calculated to prevent slipping. It also follows that when it is desired 20 to replace the sections having tap layers of rubber with those having tap layers of leather the same may be readily accomplished without the employment of skilled labor or tools.

25 It will be appreciated from the foregoing that my improved heel is simple and inexpensive in construction and in appearance is similar to the ordinary heel made entirely of leather. It will also be appreciated that the 30 improved heel is hollow, and therefore does not add materially to the weight of the shoe to which it is applied.

In Fig. 7 of the drawings I have illustrated a modification in which a spring *D'* is 35 employed to fasten the removable section *C'* in its proper position on the body or permanently-connected section *B'*. The said spring *D'* is connected to the metallic frame or plate *m'* of the section *C'* and normally 40 rests in the position shown, so as to engage the front cross-bar *h'* of the metallic frame of the body *B'*, and thereby effectually prevent the removable section being drawn out of engagement with said body. With this construction 45 it is simply necessary in order to release the section *C'* to pass a suitable instrument through the coincident apertures *x y* in the shoe bottom and body or permanently-connected heel-section *B'* and press 50 the spring *D'* downwardly a sufficient distance to enable it to clear the frame-bar *h'* when the section *C'* is drawn forwardly.

I have entered into a detail description of the construction and relative arrangement 55 of the parts of my improved heel in order to impart a full, clear, and exact understanding of the same. I do not desire, however, to be understood as confining myself to such specific construction and arrangements of 60 parts, as such changes or modifications may be made in practice as fairly fall within the scope of my invention.

Having thus described my invention, what I claim is—

1. In a heel for boots and shoes, a body or 65 section fixed on the boot or shoe and comprising an upper layer of leather, a metallic frame of less size than the leather layer connected to the under side of said layer, and a strip of leather arranged below and connected 70 to the leather layer and covering the sides and rear portion of the metallic frame, a removable section comprising a tap layer of suitable material, and a metallic plate connected to said tap layer, and means for detachably connecting the metallic plate of the removable section and the metallic frame of the body or fixed section, substantially as specified.

2. In a heel for boots and shoes, a body or 80 section fixed on the boot or shoe and comprising an upper layer of leather, a metallic frame of less size than the leather layer connected to the under side of said layer and having a curved portion provided in its inner side with a groove, and a curved strip of leather arranged below and connected to the leather layer and covering the curved portion of the metallic frame, a removable section comprising a tap layer of suitable material, and a metallic plate connected to said tap layer and having a flange adapted to enter the groove in the metallic frame of the body, and suitable means for holding the removable section against casual movement 95 with respect to the body, substantially as specified.

3. In a heel for boots and shoes, a body or 100 section fixed on the boot or shoe and comprising a metallic frame having a curved portion provided in its inner side with a groove, and also having an aperture in its forward portion and a recess in its under side in communication with said aperture, a removable section comprising a tap layer of suitable 105 material, and a metallic frame or plate having an aperture adapted to coincide with that of the metallic frame of the body, and a flange adapted to enter the groove in the metallic frame of the body, and a fastener 110 comprising a cylindrical portion adapted to normally rest in the apertures in the frames of the sections, and a lateral projection adapted to normally rest in the recess of the frame of the body or fixed section, substantially as specified.

In testimony whereof I have hereunto set my hand in presence of two subscribing witnesses.

FLOYD J. PARKER.
